UNITED STATES PATENT OFFICE.

THEOPHILE PAQUETTE, OF WEBSTER, MASSACHUSETTS.

SIGNAL.

No. 807,046.

Specification of Letters Patent.

Patented Dec. 12, 1905.

Application filed August 3, 1904. Serial No. 219,396.

To all whom it may concern:

Be it known that I, THEOPHILE PAQUETTE, a citizen of the United States of America, residing at Webster, in the county of Worcester 5 and State of Massachusetts, have invented certain new and useful Improvements in Signals, of which the following is a specification.

My invention relates to an improvement in signals, and more particularly to that class of 10 signals known as "leak-alarms," the object being to provide a device of such nature that upon the rise of water or other fluid above a predetermined height a signal will be given to notify persons of such fact.

15 I have shown my device as applied to the catch-basins or drip-pans used in connection with refrigerators; but it will be obvious that my invention is not confined solely to this employment, but is capable of a widely-exten- 20 ded use.

25 My invention consists principally of a combination, with a suitable support, of a signaling device, a float or other suitable medium operated by the rising water, means connect- 30 ing the float and signal to prevent the premature actuation thereof, and a means automatically operating to actuate the signal at the proper moment, the object being to provide a device of this nature which will sound 35 or give an alarm or in any other manner suitably indicate to the housewife or other person the condition of the receptacle to which my device is attached.

35 To this end my invention consists in cer- tain novel features of construction and combinations of parts, such as will be more fully described hereinafter and particularly pointed out in the claims.

40 In the accompanying drawings, Figure 1 is a view in end elevation, slightly in perspective, of my improved signal. Fig. 2 is a view in side elevation thereof, and Fig. 3 is a detail view of the means for normally retaining the signal in inoperative position.

45 In the drawings, A indicates a suitable receptacle, such as a drip-pan, for use with refrigerators, which receptacle is preferably, although not necessarily, provided with a beaded rim 1.

50 The signal proper comprises a base 2 of suitable dimensions, which base may consist of a wooden block provided with a pair of hangers 3 3, which are in the form of hooks adapted to lie over and embrace the edge of 55 the pan, as shown. The outer ends of the hangers pass through or are secured in any

suitable manner to the base 2 at a point somewhat removed from its inner edge, by means of which construction such inner edge is brought beneath and into engagement with the beaded rim 1, whereby to more firmly retain the device in position and prevent it from tipping under the weight imposed upon it by the trip-cup hereinafter referred to.

55 A bell 4 is secured to one end of an ex- tended resilient arm 5, the arm being pro- vided intermediate its ends with a plurality of coils or spirals 6 to increase the flexibility and resilience of the arm and at the same time to impart sufficient rigidity and tensile 70 strength thereto to prevent the weight of the bell from bending or flexing the arm to such an extent that the bell would rest on the floor or other surface. This arm projects a short distance beyond the base, the opposite end 75 of the arm being pivotally connected to the base, as at 7, by means of a screw-eye or other suitable fastening and extending, preferably, longitudinally of the base. A float-rod 8 is secured to the base, preferably at one end 80 thereof and at a point below the pivotal point of the arm, as at 9, the rod being provided near its pivoted end with a shoulder or gooseneck 10, formed therein and adapted to lie over and engage the signal-arm to prevent 85 the premature tripping thereof, as herein- after set forth. By reason of the gooseneck being located adjacent the pivotal point of the rod and in view of the length of such rod considerable pressure or leverage is brought 90 to bear upon the signal-arm to retain it in inoperative position. The free end of the float-rod, which extends into the receptacle, carries a float 11 of any suitable construction, the float adapted to rest upon the bottom of 95 the receptacle when the latter is empty and is gradually raised as the receptacle fills with water until when the water has reached a pre- determined level within the pan the gooseneck releases the signal-arm and permits the 100 arm to be raised, a crook 12 being formed in the rod adjacent the gooseneck to allow the arm a greater freedom of movement.

105 In order to effect the operation of the signal, the following mechanism is employed. A plurality of angled brackets 13 13 are se- cured to the base 2, the free ends of the brackets projecting over the edge of the receptacle A and provided with bearings 14 14 therein to receive the ends of the angled pin- 110 tles 15 15, secured to the tripping-cup 19, which is therefor pivotally supported or

hinged in the brackets. The cup is scoop-shaped, its deepest point being located approximately in alignment with and above the pintles 15 15, but having considerable area 5 gradually inclined until the inner free end of the cup, which lies above the pan, is reached. The rear wall of the cup slopes upward abruptly to a point slightly above the level of the extended inner end 17 thereof, and to this 10 rear end is secured a strap 16, which passes in a loop around the signal-arm 5 at a point between the pivotal point 7 of the arm and the coils 6, the loop being of considerable size. The strap normally rests upon the base 15 2 to serve as a support for the cup to prevent it from swinging outwardly.

The operation of my device can be easily gleaned from the foregoing; but briefly explained it is as follows: The pan or receptacle, having my invention attached thereto, is placed in position to catch the drippings or waste from a refrigerator, for instance. The water is first caught in the cup, which projects over the receptacle some distance, and 20 as soon as the cup is filled the water runs over the slightly lower inner edge 17 thereof into the pan. The weight of the water in the cup is located to one side of a line between the pintles 15 15, and thus the cup is poised off 25 its center of gravity. The weight of the water therefore tends at all times to swing the cup on its hinged supports to empty the water therefrom into the receptacle; but owing to the strap 16, which passes around the signal-arm 5 and rests upon base 2, and on account of the lever or float-rod, which holds the signal-arm down, the cup is prevented 30 from emptying itself; but as the water fills the receptacle a float, together with its 35 rod, is raised until a predetermined level is reached by the water, preferably some little distance below the rim of the receptacle, at which point the lever-rod is brought into an approximately horizontal position, moving 40 the gooseneck away from the signal-arm a sufficient distance to permit the weight of water in the trip-cup to overcome the weight of the rod 8 and raise the supporting-arm 5 into the bended portion or crook 12 of the 45 rod with a sharp jerk, whereby the clapper of the bell is oscillated to ring the bell, the arm 5 vibrating by reason of its own resiliency, the length of time the bell rings being materially increased by the resilience of the 50 coil 6.

In view of the above it will be at once apparent that I have devised a simple, inexpensive, and thoroughly efficient device for the purpose stated without the use of complicated mechanism or clockwork, the device 60 not being liable to quickly get out of order, and it is evident that many changes might be made in the form and arrangement of the several parts described without departing from the spirit and scope of my invention. Hence

I do not wish to limit myself to the exact construction herein set forth; but,

Having thus fully disclosed my invention, what I claim as new, and desire to secure by Letters Patent, is—

1. The combination with a suitable receptacle, of an alarm carried thereby, the alarm comprising a pivotally-supported, signal-carrying arm, a drip-cup connected with the arm intermediate its ends, the cup adapted to catch and normally retain a portion of the commodity subsequently received in the receptacle, and a restraining member normally locking the signal-carrying arm against movement.

2. A leak-alarm comprising a signal, a gravity-actuated tripping member for operating the signal, the signal normally overbalancing the tripping member and fluid-actuated means in contact with the signal for normally preventing its operation.

3. A leak-alarm comprising a suitably-pivoted arm, a signal operated thereby, a gravity-operated tripping means normally tending to actuate the arm and a fluid-operated restraining member in contact with the arm for normally locking it against movement.

4. The combination with a receptacle, of a pivotally-supported inherently resilient signal-carrying arm, a gravity-operated tripping member normally tending to raise the arm, and a fluid-actuated restraining member normally engaging the arm at a point separate from the point of engagement of the tripping member and arm, to lock the arm against movement.

5. A leak-alarm comprising a suitably-pivoted arm, a bell located on the arm, a coil formed in the arm intermediate the bell and the pivotal point of the arm, a gravity-operated tripping means normally tending to actuate the arm to oscillate the bell, and a fluid-actuated restraining means for normally locking the arm against movement.

6. A leak-alarm comprising a signal, a gravity-operated tripping means normally tending to actuate the signal, a suitably-pivoted lever-rod, a gooseneck or shoulder on the lever-rod, adapted to normally engage and lock the signal against movement and a fluid-operated member carried on the lever-rod for releasing the shoulder and signal.

7. A leak-alarm comprising a signal, a gravity-operated means normally tending to actuate the signal, a pivotally-mounted lever-rod, a shoulder formed on the rod adjacent its pivotal point, the shoulder normally adapted to engage and lock the signal against movement and fluid-actuated member carried by the rod for moving the latter to release the shoulder and signal.

8. A leak-alarm comprising a signal-operating arm, a gravity-operated means normally tending to actuate the signal-arm, a pivotally-mounted rod, a shoulder formed in the rod and normally adapted to engage the signal-

arm to prevent its movement, a bent or recessed portion located adjacent the shoulder and a fluid-operated member connected with the rod and adapted to move the rod to cause 5 the disengagement of the shoulder and signal-arm, the tripping means adapted to move the signal-arm within the space inclosed by the recessed portion of the rod.

9. The combination with a suitable drip-catcher receptacle, of a base removably secured thereto, an arm pivotally secured to the base, a signal actuated by the arm, a gravity-operated tripping means normally tending to actuate the arm, a rod pivotally secured to the 15 base at a point beneath the arm, locking means on the rod normally adapted to engage the arm to prevent its movement and a fluid-actuated member connected to the rod for moving the locking means out of engagement with the 20 arm.

10. The combination with a suitable receptacle having a beaded rim, of a base, hangers secured to the base within its inner edge, the hangers adapted to embrace the edge of the 25 receptacle, the inner edge of the base adapted to take beneath the beaded rim, a signal-actuating arm, means normally tending to operate the signal-arm and fluid-actuated restraining means normally adapted to lock the arm 30 against movement.

11. The combination with a suitable receptacle, of a base removably secured thereon, a signal-arm mounted on the base, brackets mounted on the base, a trip-cup, pintles carried by the cup and hinged in the brackets, means loosely connecting the trip-cup and arm and fluid-actuated restraining means normally locking the arm against movement.

12. The combination with a suitable receptacle, of a base mounted thereon, a signal-arm, a signal operated by the arm, a trip-cup, a strap secured to the trip-cup and passing loosely around the arm, the strap engaging the base to support the cup, and fluid-actuated means normally engaging the arm to prevent its movement.

13. The combination with a receptacle, of a

suitably-supported signal-arm, a signal operated thereby, a scoop-shaped trip-cup, the trip-cup pivotally mounted to one side of its center of gravity, means connecting the trip-cup and arm and normally tending to actuate the latter, and fluid-actuated means normally locking the arm against movement.

14. The combination with a catch-basin, of a hinge-supported trip-cup offset from its center of gravity, the trip-cup adapted to be filled with liquid, a signal-operating arm, means connecting the trip-cup and arm and a fluid-operated restraining member normally locking the arm against movement.

15. The combination with a catch-basin, of a pivotally-supported trip-cup offset from its center of gravity, the trip-cup projecting over the catch-basin and adapted to catch and retain a portion of the liquid designed to be received by the catch-basin, a signal-operating arm, means connecting the trip-cup and arm, and fluid-actuated restraining means normally engaging the arm to prevent its movement.

16. A leak-alarm comprising a gravity-operated tripping member, adapted to be filled with a dischargeable commodity, a signal-arm with which the member is connected, a signal carried by the arm and of greater weight than the tripping member when the latter is empty, and a fluid-actuated restraining member for normally preventing the operation of the signal-arm.

17. The combination with a fluid-receiving receptacle, of a pivotally-supported drip-cup adapted to primarily receive the fluid and subsequently discharge it into the receptacle, a signal, which the drip-cup normally tends to operate, and an automatically-operated member normally locking the signal against premature actuation.

In testimony whereof I have signed my name to this specification in the presence of two subscribing witnesses.

THEOPHILE PAQUETTE.
